UNITED STATES PATENT OFFICE.

WILLIAM P. BRENEMAN AND HERBERT G. ROWELL, OF AUBURN, MAINE.

MOP-HOLDER.

1,374,814.

Specification of Letters Patent.

Patented Apr. 12, 1921.

Application filed December 27, 1920. Serial No. 433,173.

To all whom it may concern:

Be it known that we, WILLIAM P. BRENEMAN and HERBERT G. ROWELL, citizens of the United States, residing at Auburn, in the county of Androscoggin and State of Maine, have invented certain new and useful Improvements in Mop-Holders, of which the following is a specification.

Our invention relates to a new and useful improvement in mop holders and has for an object to provide a holder that is exceedingly simple in construction, quickly and readily assembled, and relatively cheap to manufacture.

Another object of our invention is to provide a mop holder that may be quickly opened for the insertion of the mop and also quickly and easily closed; furthermore to provide a mop holder wherein, when open there is a relatively large space between the head piece and the clamp for the insertion of the mop.

Still another object of our invention is to provide a mop holder having the head piece formed of wire and the clamp member also formed of wire and the latter provided with offsets near its outer bar so that the strain on the head piece when closing the mop head will be in the direction of the handle rather than transversely to the head, which would cause the head to soon become bent from its true shape, and become practically useless.

Still another object of our invention is to so provide the head and the clamp member that when the mop holder is closed on insertion of the mop, the strain on the head will tend to force the head more tightly on the handle rather than loosen the head which is common to so many mop holders of different constructions.

With these and other objects in view our invention consists in certain new and novel constructions and combinations of parts as will be hereinafter more fully described and pointed out in the claims.

Referring now to the drawings showing the preferred form of the invention;

Figure 1 is a top plan view of our improved mop holder, the same being shown in its closed or mop holding position;

Fig. 2 is a side elevation of our improved mop holder, the parts being in a similar or closed position;

Fig. 3 is a side elevation showing the

mop holder in its open or receiving position for the mop.

Referring now to the several figures, there is shown the usual handle 1 which is slightly reduced as at 2, and on which is positioned the wire head 3 which head comprises the spiral windings 4 tightly surrounding the reduced portion 2 of the mop handle, and the remainder of the head then bent to form the elongated loop and outer bar 5. A small staple 6 is shown to prevent the turning of the head on the handle. Passing through the opposite sides of the head piece 3 is the clamp member 7 which is provided with the rearwardly extending arms 8 which are then bent inwardly as at 9, and are again bent as at 10, approximately parallel to the handle, the ends of the arms being looped as at 11 for the reception of the ends 12 of what I term the bridge piece 13. This bridge piece is also formed of wire, substantially U-shaped and passing over the central portion thereof is the retaining member 14 which is securely riveted to the handle 1.

Referring again to the clamp member 7 and to one of the most important features of the invention there is shown near the outer ends of the two arms 8 the offsets 15, and just beyond these offset portions the arms of the clamp again extend upwardly as at 16 (Fig. 2) and across to form the outer bar 17. Near the opposite ends of the arms 8 they are again slightly bent downwardly as at 18, the two offsets beside other functions, making it possible to use a shorter bridge member 13 than would otherwise be the case.

The opening and closing operation of the mop holder is exceedingly simple, it being perfectly obvious that when the clamping member is in the position as shown in Fig. 3 and the mop inserted it is only necessary to swing the bridge member 13 rearwardly, it being pivoted in the retaining member 14 and as soon as the bridge piece passes downwardly beyond the axis of the pivotal point, it will tightly clamp the mop in position, and of course cannot become accidentally disengaged.

In accomplishing this clamping action, however, the offsets 15 heretofore referred to perform an important function in that they allow the end bar 17 to contact with the mop (not shown) against the outer bar 110

5 of the head piece 3, and as the arms 8 are drawn rearwardly by the pivoted bridge the strain will be on the head piece but in the direction parallel to the handle. This 5 will readily be seen, inasmuch as the fulcrum of the bridge piece is at the retaining member and as the bridge piece is pushed rearwardly, the arms must be drawn inwardly and the end bar 17 of the clamp 10 member resting against the mop, which in turn is against the outer bar of the head piece will tend to force the whole head piece inwardly on the handle.

If it were not for these offset portions 15 15, it will be seen that when the clamping member was operated it would tend to force the head laterally of the handle rather than inwardly. From the above it will be seen that by forming the mop holder with the 20 described offsets and so fulcruming the clamp, the strain on the head is parallel to the handle thereby greatly prolonging the life of the mop holder. Also the thicker the mop the tighter it will be held and the 25 tighter the head piece will be held on the handle. The staple snugly holds the head piece from any turning action and no extraneous means are necessary for holding the head piece in position.

30 We are aware that it is old in the art to provide a mop holder formed of wire and wherein a clamping member is brought downwardly beyond a horizontal axis to thereby clamp a mop in position, and we 35 do not broadly claim our invention as such, but what we do claim and desire to secure by Letters Patent is:

1. A mop holder comprising a handle, a head piece secured to said handle, a single 40 clamp member passing through said head

piece and said clamp member comprising two side arms and an outer cross bar, a retaining member on said handle, a bridge piece connecting the side arms of said clamp member, a portion of said bridge piece fitting beneath the said retaining member, the said side arms extending parallel with the handle for a greater portion of their length when said clamp member is in its closed position, and said side arms provided with 45 offset portions near their outer end, passing beneath the outer portion of the headpiece, and again extending upwardly to the cross bar, which cross bar is in a plane above that of the plane of the outer portion of the 50 head piece.

2. A mop holder comprising a handle, a head piece secured to said handle, said head piece in the shape of an elongated loop, a single clamp member having side arms and 55 an outer cross bar, the side arms extending through the said loop portion of the head piece, said side arms having off set portions near their outer ends and adapted to pass below the outer bar of the loop of the head 60 piece, said arms again extending at an angle to the off set portion and the outer bar connecting with said arms being in a plane above that of the plane of the outer bar of the loop, a fixed retaining member on the 65 handle, a bridge piece connecting the inner ends of said side arms of the clamp member and a portion of said bridge piece passing beneath the retaining member for fulcrumming the clamp member when said bridge 70 piece is manipulated.

In testimony whereof we affix our signatures.

WILLIAM P. BRENEMAN.
HERBERT G. ROWELL.
